UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

DRAG ROLL AND CLEARING PLATE FOR LOOMS.

Application filed August 10, 1926. Serial No. 128,490.

This invention relates to drag roll looms wherein the warp sheet is led from the warp beam around an auxiliary drag roll and then about a portion of the main drag roll as it 5 passes towards the shedding mechanism, and the invention is more particularly directed to the means for collecting lint, dirt and other foreign substances detached from the warp sheet, so that such foreign matter shall 10 not be carried along with the warp sheet into the woven cloth.

In weaving certain characters of fabrics, such, for instance, as duck and other cloths employing heavier warp threads, it is now 15 the usual practice to provide a main and an auxiliary drag roll located above the warp beam and to pass the warp sheet over the auxiliary drag roll, then about the main drag roll, to spread the sheet and maintain 20 the desired amount of tension on the warp threads. In the use of warps of this general character much lint, dirt and other foreign matter is detached from the warp threads, and in the absence of means to prevent may 25 be carried with the warp sheet and be finally woven into the cloth.

It is therefore one of the objects of the present invention to provide a construction which will take care of lint, dirt and foreign 30 substances dropped from the warp sheet as it passes about the drag rolls on its way to the shedding mechanism and to collect such undesirable substances in a manner such that they may be readily removed from the 35 loom.

The invention and new combination of parts will best be made clear from the following description and the accompanying drawings of one good form thereof.

40 In the drawings:

Fig. 1 is a perspective view at the rear portion of a loom containing the present invention; and

Fig. 2 is a cross-sectional view showing 45 the relation of parts constituting the present invention.

In drag roll looms the main and auxiliary drag rolls are customarily mounted in fixed bearings above the warp beam, and 50 in some instances such drag rolls have been made of tubing or cylindrical hollow pipe, and in order to secure the desired tension upon the warp sheet, the warp is led from the warp beam about the auxiliary drag roll, then backwardly under and over the

main drag roll towards the shed forming mechanism. In accordance with the present invention, the main drag roll is formed as a hollow cylinder mounted in fixed bearings and having a longitudinally extending slot 60 or opening in the upper portion thereof into which lint, dirt or other foreign matter may fall and from which it may be readily removed, and associated with such drag roll the present invention provides a lint collecting trough interposed between the main and auxiliary drag rolls, the construction being such that as the sheet of warp passes over the rear portion of scraper of the lint collecting trough, the lint and other foreign 65 substances detached from the warp sheet may fall directly into the opening in the main drag roll, and as the warp sheet passes over the forward scraper forming a part of the lint collecting trough, any additional 70 matter detached from the warp sheet may fall into the open trough and so be readily removed.

The loom frame 1 may be of usual construction and have associated therewith a 80 bracket 2 upon which is formed a bearing 3 for the support of the journals or axial stud 4 which supports the warp beam 5, on which the warp threads *a* are wound.

Likewise secured to the loom frame at 85 each side of the loom is a bracket 6 preferably secured in fixed position by means of bolts 7 which pass through slotted openings 8 in the bracket web, so that the bracket 90 itself may be adjusted in proper position.

At the rear portion of the bracket 6 (one 95 at each side of the loom) is a support 9 to which the main drag roll 10 may be secured. In the present instance, the supports 9 (only one of which is shown) have 100 the upper and lower portions 11 and 12 partially surrounding the ends of the main drag roll, and the latter may be secured to the bracket by suitable bolts 13. In order that the main drag roll 10 may be 105 laterally adjusted into the desired position, the drag roll is provided with slots 14 extending through the terminal end portions of the drag roll, and through which the clamping bolts pass, as indicated in Fig. 1.

The main drag roll 10 is provided with a slot or opening 15 extending longitudinally of the drag roll and when the latter is in its operative position, such slot or opening 110 15 is at the upper portion of the drag roll,

as indicated in Figs. 1 and 2. In the present instance it will be noted that the slot or opening 15 has its side walls flush with the cylindrical surface of the drag roll.

5 Mounted in bearings 16 formed in the bracket 6 is the auxiliary drag roll 17 which is held from turning movement by the slabbed-off portion 18 of the auxiliary drag roll. The warp threads are led from the 10 warp beam 5 upwardly under and over the auxiliary drag roll 17, as indicated in Fig. 2, then downwardly under the main drag roll 10 and about an extended segmental surface thereof, and then towards the shedding mechanism.

20 Between the main and auxiliary drag rolls is a lint trough which may be appropriately secured in position by any suitable means, and in the present instance is shown as secured to the main drag roll by bolts 19. The lint trough 20, as above indicated, has a wide open top and when in position between the main and auxiliary drag rolls, the rear upwardly extending member 21 of the lint trough projects above the opening or slot 15 in the main drag roll, with the result that any lint, dirt or foreign matter detached by the scraping edge of the trough may fall directly into or through the opening or slot 15 in the main drag roll.

25 The lint trough has its frontwardly extending side member 22 projecting upwardly, as indicated in Figs. 1 and 2, and over it, as well as the rear wall of the trough, the warp threads *a* pass, so that both the top of the rear wall of the trough and the front wall of the trough act as scrapers for the warp sheet. Any lint, dirt or other foreign substance detached from the warp sheet by the frontwardly and upwardly extending side member of the lint trough, 30 will fall directly into the lint trough itself, as indicated in Fig. 2, and may be readily removed therefrom without disassembling the parts of the loom.

40 While, as hereinbefore stated, the lint trough may be secured in position between the main and auxiliary drag rolls by any suitable means, it is found preferable in practice to mount the lint trough upon the main drag roll with its end portions abutting against the upper member 11 of the fixed bearing 9 in which the main drag roll is supported, the result being that the lint trough is properly located and held in its operative position more particularly with respect to the opening or slot 15 in the main drag roll.

45 From the construction described it will be apparent that the main drag roll is an open-ended cylinder having a plain or unflanged opening or slot 15 for the discharge of lint and foreign substances detached by the scraper plate 21, which is independent of the main drag roll and secured in posi-

tion so that the scraper edge of the scraper plate shall detach lint and foreign substances from a sheet of warp in such position relative to the slot or opening 15 in the main drag roll that such substances may fall directly into the main drag roll. Likewise, it will be apparent that the frontwardly and upwardly extending side member of the lint trough constitutes a second scraper which directs any lint and other foreign substance detached from the warp sheet directly into the open trough, so that the warp sheet passes to the shedding mechanism and the cloth in a substantially clean condition.

50 To further insure that the foreign substances such as lint and the like may not accumulate upon the warp sheet, the present invention contemplates an apron or shield so supported that it shall rest upon the warp on the warp beam throughout the width of the loom, as more particularly illustrated in Fig. 2.

55 In the present instance, the apron 23 is secured to a rod 24 which is itself hung from the auxiliary drag roll 17 by a bridle 25, preferably one of said bridles being located near each end of the auxiliary drag rolls. The apron 23 extends sufficiently about the warp on the warp beam so that any lint or foreign matter dropping from the warp above the warp beam shall be deflected and not accumulate upon the warp. The apron 23 becomes of importance because it protects that side of the warp sheet which is not subject to the action of the scrapers, so that when the warp sheet passes over the auxiliary and main drag rolls and is subjected to the action of the scrapers, as hereinbefore described, both surfaces of the warp sheet will be clear 60 of lint and other foreign substances.

65 What is claimed is:

1. In a loom, the combination of a hollow drag roll having a longitudinally extending opening to receive lint, dirt, and the like dropped from the warp, and a lint trough extending transversely of the loom in front of said opening in the drag roll and having a scraping edge over which the warp threads pass from the drag roll to the shed forming mechanism.

2. In a loom, the combination of a hollow drag roll having a longitudinally extending opening to receive lint and the like, an auxiliary drag roll in front of the hollow drag roll, and a lint trough between the two drag rolls having a scraping edge over which the warp threads pass from the hollow drag roll to the shed forming mechanism.

3. In a loom, the combination of a hollow drag roll having a longitudinally extending opening to receive lint and the like, an auxiliary drag roll in front of the hollow drag roll, and a lint trough between

- the two drag rolls having two scraping edges over which the warp threads pass from the hollow drag roll to the shed forming mechanism.
- 5 4. In a loom, the combination of a hollow drag roll having a longitudinally extending opening to receive lint and the like, an auxiliary drag roll in front of the hollow drag roll, and a lint trough between the two drag rolls having a scraping edge extending above the longitudinal opening in the hollow drag roll over which the warp threads pass from the way to the shedding mechanism.
- 10 5. In a loom, the combination of a hollow drag roll having a longitudinal opening, a lint trough in front of the drag roll and having an upwardly extending warp scraping edge above the opening in the drag roll over which the warp threads pass from the 20 drag roll to the shedding mechanism.
- 15 6. In a loom, the combination of a hollow drag roll having a longitudinal opening, a lint trough in front of the drag roll having an upwardly extending warp scraping edge above the opening in the drag roll over which the warp threads pass from the 25 drag roll to the shedding mechanism and means for securing the lint trough in position in front of the drag roll.
- 20 7. In a loom, the combination of a hollow drag roll having a longitudinal opening, a lint trough in front of the drag roll having an upwardly extending warp scraping
- ing edge above the opening in the drag roll over which the warp threads pass 35 from the drag roll to the shedding mechanism and an apron below the lint trough to deflect any falling lint from the warp.
8. In a loom, the combination of a hollow drag roll having a longitudinally extending opening through its cylindrical wall, an auxiliary drag roll in front of the hollow drag roll, a lint trough open at its top and located between the two drag rolls, a scraping edge formed on the lint trough 40 and extending above the opening in the hollow drag roll, and a second scraping edge 45 on the lint trough frontward of the other scraping edge.
9. In a drag roll loom, the combination 50 of a main hollow drag roll having a longitudinally extending opening for the passage of lint and foreign substances detached from the warp sheet, a lint trough made separate from the drag roll and extending transversely of the loom in front of the opening in the drag roll and having a warp scraper, and means for detachably securing the lint trough above the opening in the main drag roll so that lint 55 scraped from the warp sheet by the warp scraper may fall through the opening in the main drag roll.

In testimony whereof, I have signed my name to this specification.

HARRY A. DAVIS.
